STEAM ENGINE VALVE

William F. Kiesel, Jr., Hollidaysburg, Pa.

Original application August 3, 1927, Serial No. 210,412. Divided and this application June 3, 1929, Serial No. 368,011

8 Claims. (Cl. 121—142)

This invention relates to the valves for steam engines and more particularly to valves intended to be used on locomotives operating at very high steam pressures. The present application is a 5 division of my copending application Serial No. 210,412, filed August 3, 1927.

It is a general object of the present invention to provide a novel and improved valve for locomotive engines together with operating gear for 10 the same.

More particularly, it is an object of the invention to provide, in a locomotive, a main valve adapted to control the flow of live and exhaust steam to and from a cylinder, together with an 15 auxiliary valve whose sole function is to control the cut-off and to limit the same to a small percentage of the stroke at moderate and high speeds.

A further object of the invention consists in 20 providing means to be used in connection with auxiliary and limiting cut-off valves, to supply steam throughout substantially the full stroke of the piston for starting purposes.

One feature of the invention comprises a novel 25 arrangement for actuating the auxiliary cut-off valve from the linkage mechanism of the main valve.

A further feature of the invention comprises the arrangement of an auxiliary cut-off valve 30 controlling the admission of live steam into what may be termed the receiver volume of the main valve chamber.

Another and further object of the invention consists in the provision of novel means for bypassing live steam around the cut-off valve to 35 the receiver volume of the main valve chamber on starting, when the auxiliary cut-off valve produces a cut-off too early in the stroke of the piston to provide adequate power.

40 Other and further features and objects of the invention will be more apparent to those skilled in the art upon consideration of the accompanying drawings and following specification wherein are disclosed several exemplary embodiments of 45 the invention with the understanding that such changes may be made therein as fall within the scope of the appended claims without departing from the spirit of the invention.

In said drawings:

50 Figure 1 is a side elevation of a portion of a locomotive disclosing a cylinder, the cylinder valves, some of the drivers, the connecting rod and the valve operating mechanism, or gear, which is of the Walschaert type;

55 Figure 2 is a longitudinal vertical section

through the main valve showing in detail the drive mechanism for it and the auxiliary valve; Figure 3 is a transverse vertical section on broken line 3—3 of Figure 2; and

Figure 4 is a longitudinal section through the 60 auxiliary valve and the main valve taken on broken line 4—4 of Figure 3.

With the use of very high pressure steam, the conventional form of valve and valve motion, now used on locomotives, is not satisfactory to 65 realize the expansion possibilities of such pressure, and some means must be provided to achieve earlier cut-off than is now possible without excessive throttling of the steam. The conventional slide valve either of the D or piston type, 70 operated by any form of valve gear, such as the Walschaert type, has the various events which it controls so interconnected that a change in the hook-up to change, for instance, the cut-off, causes a change in the various other events, notably 75 release and compression. If, with admission occurring slightly before dead center, an attempt is made to provide cut-off early in the stroke, the angle of advance, determined by these two events, is large and causes either release or compression or both to be early. If one is improved, it must be at the expense of the other. On high speed engines, a rather high compression is desired to absorb the kinetic energy of the reciprocating parts at the end of the strokes, but on 80 lower speed engines such compression is not only unnecessary but undesirable because it reduces the amount of work per stroke. A locomotive is 85 essentially a variable speed machine, and it will be seen that an attempt to obtain an early cut-off at moderate speeds, as required for economy, will increase the compression too greatly and also seriously advance the release. The release should not be advanced materially where using 90 very high pressure steam, for it materially reduces the economy.

The present invention contemplates overcoming the above and other difficulties by the use of an auxiliary or cut-off valve arranged between the main valve, which may be of any desired 100 form, and the steam pipe and actuating this cut-off valve from the same link motion that actuates the main valve. According to this invention the main valve is so arranged as to permit cut-offs varying from small amounts to a predetermined 105 maximum of 80% to 90% as desired, whereas the cut-off valve is so arranged as to admit steam up to about 10% of the piston travel when the link block is in mid-position and up to about 25% when the link block is in either of its ex- 110

trete positions. This valve controls the admission of steam into a definitely determined space, in the case shown, the main valve chamber volume surrounding the main valve barrel. The 5 main valve disclosed is of the inside admission type and the space surrounding the main barrel thereof, and into which steam is admitted by the cut-off valve will hereinafter be designated the receiver volume. In operation, after closing of 10 the cut-off valve, the receiver volume and the portion of the cylinder up to the piston will be filled with live steam which then expands and moves the piston until the main valve closes and causes cut-off. Further expansion will then occur 15 in the cylinder volume alone, and will continue until the main valve opens for release.

However, when starting and travelling slowly under a heavy load, it is desirable to permit a maximum cut-off of at least 80% which the 20 main valve will allow, but which the cut-off valve will not allow. Hence some means is provided to allow by-passing or leakage of steam from the source of steam supply into the receiver volume for starting purposes, but this means is 25 provided with a constriction so that the amount of steam flow therethrough will produce but little effect when running at high speeds and, therefore, the cut-off as determined by the auxiliary cut-off valve will be effective.

30 Referring to the drawings, there will be seen at 10 the conventional cylinder of a locomotive within which is located the piston 10' driving the drivers 11 through the piston rod 12, the connecting rod 13 and the pitman rods 14. The rod 13 is journaled on crank pin 15 secured to the face of one of the drivers. The connection between the connecting rod 13 and the piston rod 12 is effected at the cross head 16 which slides in the guides 17.

40 Steam is admitted to either end of the cylinder as required and exhausted therefrom through the ports 18 controlled by the slide valve 19, reciprocable in a valve chamber 20, and adapted to be moved in timed relation to the piston by a valve 45 rod 21 passing through a stuffing box 22 in one head of the chamber. The valve 19 may be of any of the well known and conventional types, the one shown being a piston valve to provide inside admission and outside exhaust. It is not 50 believed to be necessary to here describe the operation of the valve 19 other than to say that it is so designed as to allow cut-off up to substantially 80% to 90% of the piston stroke, and can be, by its linkage, adjusted to produce cut-offs at fairly 55 small percentages of the piston stroke, say about 20% to 25%. Adjustments of the linkage to thus vary the cut-off through this range has but little effect on admission, release and compression.

Motion is imparted to the valve in timed relation to the motion of the piston by means of the well known Walschaert valve gear, comprising the eccentric rod 24 driven from the eccentric pin 25 and serving to rock the link 26 trunnioned at 27 and provided with an arcuate slot 28 in which the link block 29 secured to one end of the radius rod 30 is adjustably positioned. A link 31 is attached to the cross head and enables the motion of this cross head to be combined with the motion of the radius rod obtained from the 65 eccentric pin by means of the "lap and lead" lever 32 having its ends pivoted respectively to one end of each radius rod 30 and the link 31. At 33 the lap and lead lever 32 is pivotally connected to a slider 34 operating in ways 35 in the 70 brackets 36 extending from the stuffing-box-end

head 37 of the valve chamber 20. It will be seen that the lap and lead lever floats between the link 31 and the radius rod 30 and is supported by means of the slider 34 to which it imparts the combination of the motions of the cross head and the eccentric pin. The amount and direction of movement of the radius rod 30 may be changed by varying the position of the link block 29 in the slot 28 in the link by means of the lifting link 30' attached to the bell crank lever 38, which is operated by the reach rod 39 leading to the cab. 80

In Fig. 4 is shown the auxiliary, or cut-off valve comprising a hollow cylinder 40 adapted to be reciprocated within the sleeve 41 in the auxiliary valve housing 42. The valve is open at both 90 ends in order that steam may flow through the same from the main steam inlet 43. It is provided with the packing rings 41' to maintain a steam tight fit with the sleeve. When the valve is moved a sufficient distance from its center 95 position in either direction, steam may flow by the end of the valve and through openings in the sleeve into the annular passage 44 which communicates by way of the port 44' with the central space 45 surrounding the main piston valve 19 100 which distributes the same to either end of the cylinder in a well known manner.

Motion is imparted to the cut-off valve in the desired relation to the motion of the main valve by means of the linkage best shown in Fig. 2. 105 The arms 36 extending from the head of the main valve chamber to form guides for the slider are bent upwardly to form the trunnions 47 between which is pivoted the lever 48 whose lower end is connected by a link 49 to an intermediate 110 point on the lap and lead lever 32. The upper end of the lever 48 is connected, by a link 50, to the lower end of the arm 51, secured to the rock shaft 52, best shown in Fig. 4. This shaft passes through a gland 53 in the wall of the extension 115 54, near the top, and at one end, of the auxiliary valve housing. The arm 55 is secured to the inner end of the rock shaft 52. The lower end of this arm 55 is connected, by a link 57 which passes through the hollow valve member 40, to the trunnions 58 on the far end of that valve member. It will thus be seen that the auxiliary valve will move in unison with the main valve, but not necessarily in exact synchronism therewith. The rock shaft 52 together with its two arms 51 120 and 55 is used in order to eliminate a stuffing-box and its chances for leakage when subjected to the extremely high pressure steam in the auxiliary valve chamber. A tight fit where the rock shaft passes through the gland 53 is obtained 125 by means of a collar secured to the rock shaft and having a ground fit with the inner surface of the gland against which it is maintained by steam pressure in a well known manner.

The operation of the parts of the structure so far described, will be readily understood. It will be seen that the cut-off valve controls absolutely the flow of steam into the space 45 surrounding the main valve, which space has been termed the "receiver volume", and which has less than 130 one third of the cylinder volume. The cut-off valve is timed to open considerably before "admission", as determined by the main valve, so as to fill the receiver volume and to insure that the cut-off valve will govern only the cut-off. Upon "admission" by the main valve, steam 135 expands from the receiver volume and flows into the cylinder followed immediately by a flow of steam directly from the steam pipe through the cut-off valve and the passage 44 into the space 140 145 150

45 and thence into the cylinder until cut-off is effected by the auxiliary valve, after which steam, both in the cylinder and in the receiver volume, will expand until cut-off is effected by 5 the main valve 19, after which further expansion will take place in the cylinder only, until release is effected by the main valve.

The main valve, as before stated, may have a maximum cut-off of from 80% to 90% when the 10 link block is at a maximum distance from the trunnions in either direction, and will preferably have a minimum cut-off, when fully hooked up, substantially equal to the maximum cut-off of the auxiliary valve, i.e., about 25%. The main 15 valve thus has a variation between these limits rather than between the wider limits ordinarily necessary for economical operation. The correlated events controlled by the main valve can thus be better adjusted and proportioned, and 20 furthermore less throttling of the steam takes place during admission.

The auxiliary valve is designed to provide cut-offs varying from substantially 10% to 25% of the piston stroke in accordance with the position 25 of the link block. The percentage of cut-off varies with movement of the link block in the link in the same manner as does that of the main valve. With this arrangement, it will be seen that while the port opening afforded by 30 the cut-off valve is large and provides a satisfactory flow of steam at the smaller cut-offs without undue throttling, this valve, nevertheless, limits the cut-off to a maximum of about 25% when the linkage is in extreme position and 35 can reduce the same to a minimum of substantially 10% when the linkage is fully hooked up, but maximum cut-off of around 80% cannot be obtained for starting purposes. It is essential that a cut-off of such proportions be available 40 for starting under heavy loads and on steep grades.

Steam for cut-offs up to substantially 80%, or the maximum allowed by the main valve design and setting may be provided by a bleeder, or 45 port 62, in the wall of the auxiliary valve 40, as shown in Fig. 4. This port is positioned in such a manner, in relation to the passage 44, that it is always in communication with this 50 passage when the passage is covered by the valve.

This bleeder is of such size as to provide sufficient steam to the receiver after closure of the cut-off valve, for cut-offs up to the maximum allowed by the main valve when starting and when the locomotive is moving at very slow 55 speeds. However, the port is so restricted that at speeds of above 10 miles an hour the amount of steam flowing through the bleeder is inconsequential, due to the short time occupied by each stroke, and has almost no effect on the steam distribution which is then wholly determined by the auxiliary valve, whereas at starting and at very low speeds, the cut-off is wholly determined by the main valve.

The advantages of the construction above described will be readily appreciated by those skilled in the art. It will be seen that all of the advantages are obtained with but slight additions to the usual mechanism. The apparatus necessary for controlling the auxiliary or cut-off valve is extremely simple and comprises but three parts. The separate cut-off valve enables a high pressure locomotive or, in fact, any steam engine of variable speed to be operated more economically and with better main valve func-

tioning. It allows an earlier cut-off than is possible with a conventional form of single valve controlled by the usual linkage and provides for quicker opening and closing of the ports without deleterious effects on the conjugate functions of the main valve. The provision of a "receiver volume" of about one-third of the cylinder capacity allows for a better use of the full expansion possibilities of the very high pressure steam. The advantages of late cut-off for starting are obtained in a simple manner without adding to the necessary manual controls in the cab.

Having thus described the invention, what is claimed as new and desired to be secured by Letters Patent is:

1. In a steam locomotive, in combination, a cylinder, a piston reciprocable therein, a slide valve controlling live and exhaust steam for said cylinder and a separate cut-off valve between said slide valve and the source of live steam, said cut-off valve being arranged to provide maximum cut-off less than that required for starting, and provided by the main valve and means in said cut-off valve having a constant admission area to admit sufficient steam to said slide valve up to the required piston displacement for operation at slow speeds only.

2. In a steam locomotive, in combination, a cylinder, a piston reciprocable therein, a main valve adapted to control admission and to provide the maximum cut-off ever required, a cut-off valve between the source of steam and the main valve arranged to provide as its maximum cut-off that required at normal operating speeds, and means in said cut-off valve having a constant admission area to admit sufficient steam to said main valve for starting purposes only during the period from cut-off by the cut-off valve to cut-off by the main valve.

3. In a steam locomotive, in combination, a cylinder, a piston reciprocable therein, a main valve adapted to control admission and to provide the maximum cut-off ever required, a cut-off valve between the source of steam and the main valve arranged to provide as its maximum cut-off that required at normal operating speeds, and means including a port of such size in said cut-off valve as to be effective at low speeds only to admit steam to the main valve for starting purposes during the period from cut-off by the cut-off valve to cut-off by the main valve.

4. In a locomotive, in combination, a pair of cylinders, pistons therein adapted to operate with cranks displaced at a fixed angle, a main valve chamber for each cylinder, a valve in each main valve chamber, a cut-off valve chamber adjacent each main valve chamber, a cut-off valve therein adapted to control the flow of steam to said main valve chamber and adapted to always give early cut-off and means in said valve of fixed flow area to pass a small quantity of steam to the main valve chamber after cut-off by the cut-off valve to admit sufficient steam for operating at low speeds until cut-off by the main valve.

5. In a locomotive, in combination, a cylinder, a piston operative therein, a main valve arranged to "cut-off" in full gear after the piston has completed at least two-thirds of its stroke, a cut-off valve arranged to "cut-off" steam to the main valve before the piston has completed one-third of its stroke, a steam space between the cut-off valve and the main valve, and means independent of the position of the cut-off valve after cut-off to admit a limited quantity of steam through said

cut-off valve to said space after "cut-off" by said cut-off valve.

6. In a locomotive, in combination, a cylinder, a piston operative therein, a main valve chamber, a valve operative therein, a cut-off valve chamber adapted to be supplied with live steam, a passage between a port intermediate the ends of said cut-off valve chamber and a port in the main valve chamber, a hollow open-ended valve member in said cut-off valve chamber normally covering said port therein, means to reciprocate said valve in unison with said main valve to uncover said port and a bleeder in said cut-off valve always open to a fixed area to said port when the port is covered by the valve.

7. In a locomotive, in combination, a cylinder, a piston operative therein, a main valve chamber, a valve operative therein to provide late cut-off, a cut-off valve chamber adapted to be supplied with live steam, a port through a wall of said chamber connected by a passage to said main valve chamber, a valve member in said chamber to cooperate with said port to control the normal flow of steam to said main valve to always pro-

vide early cut-off and a bleeder passage through said valve to always register with said port with constant area when said port is covered by said valve, said passage having such steam capacity as to provide sufficient steam to operate the locomotive with main valve cut-off at low speeds but with substantially cut-off valve cut-off at high speeds.

8. In a steam locomotive, in combination, a cylinder, a piston reciprocable therein, a connecting rod and crank, a main valve adapted to control admission and adjustable to vary cut-off and receiving a component of its motion from said crank, a cut-off valve controlling a port between the source of steam and the main valve arranged to provide as its maximum cut-off that required at normal operating speeds and obtaining its movement from the drive for the main valve, and a passage of fixed admission area from the cut-off valve chamber to the main valve chamber so disposed that when the cut-off valve covers said port said passage provides for a constant measured flow of steam to the main valve chamber.
